United States Patent Office

Des. 197,886
Patented Apr. 7, 1964

197,886

BODY FOR A TRACTOR

Lovell R. Simmons, Horace Hilton Ray, and Lester Rasberry, Jackson, Miss., assignors to M-R-S Manufacturing Company, Flora, Miss., a corporation of Delaware

Filed May 9, 1963, Ser. No. 74,820

Term of patent 14 years

(Cl. D14—3)

FIG. 1 is a rear perspective view of a body for a tractor showing our new design.

FIG. 2 is a front view thereof; and

FIG. 3 is a side view thereof.

The dominant features of our design reside in the portions illustrated in solid lines.

We claim:

The ornamental design for a body for a tractor, substantially as shown and described.
